(57) **CLAIM**

The ornamental design for a case and cartridge gauge, as shown and described.

DESCRIPTION

FIG. 1 is a perspective bottom view of case and cartridge gauge.

FIG. 2 is a rear elevation view of the embodiment shown in FIG. 1.

FIG. 3 is a front elevation view of the embodiment shown in FIG. 1.

FIG. 4 is a left side elevation view of the embodiment shown in FIG. 1.

FIG. 5 is a right side elevation view of the embodiment shown in FIG. 1.

FIG. 6 is a bottom view of the embodiment shown in FIG. 1.

FIG. 7 is a top view of the embodiment shown in FIG. 1.

FIG. 8 is another perspective view showing the top of the embodiment shown in FIG. 1.

FIG. 9 is a perspective view showing the top of the embodiment shown in FIG. 1 in a configuration of use.

FIG. 10 is a perspective view showing the top of the embodiment shown in FIG. 1 in a configuration of use; and, FIG. 11 is a perspective view showing the bottom of the embodiment shown in FIG. 1 in a configuration of use.

The broken lines show portions of the case and cartridge gauge that form no part of the claimed design. The broken lines showing of a cartridge in FIGS. 9-11 represents environmental subject matter that forms no part of the claimed design.

1 Claim, 11 Drawing Sheets
